DEVICE FOR FLANGING CAN BODIES

Olinto J. Tofanelli, Oakland, Calif., assignor to
American Can Company, New York, N. Y., a
corporation of New Jersey

Application October 2, 1945, Serial No. 619,795

6 Claims. (Cl. 153—25)

1

The present invention relates to a device for flanging can or container bodies and has particular reference to a flanging head having a sectional outside support flanging ring.

In the manufacture of tearing strip cans it is sometimes necessary for desired results to place the encircling tearing strip close to an end of the cans. With such a location of the tearing strip the outer score line, which defines the outer boundary of the strip, is disposed close to the flange edge of the can body from which the can is made and is liable to rupture during the flanging of the can body.

In the can making industry the procedure usually followed in flanging can bodies is to make the pilot of the flanging head slightly larger than the inside diameter of the can body and then force the body over the pilot. This sometimes strains the body and subsequently results in open side seam laps either immediately after manufacture or during storage. It is this strain on the body which also ruptures the tearing strip score lines. When pilots of a dimension slightly smaller than the inside diameter of the can body have been used, considerable difficulty is encountered in having the flange turn inwardly instead of outwardly with its resultant waste of material.

The instant invention contemplates overcoming these difficulties by providing a flanging head with a sectional support ring surrounding a pilot of a dimension smaller than the can body to be flanged so that injurious strains on the body will be eliminated while at the same time the wall of the body adjacent the tearing strip will be confined and reenforced during the flanging operation, thereby preventing rupture of the body wall in the tearing strip score lines.

An object of the invention is the provision of a head for flanging can bodies having tearing strips wherein the head is formed with a sectional outside support flanging ring, engageable with the exterior surface of the tearing strip portion of a can body to reenforce and confine the body wall against rupture in the tearing strip score lines during the body flanging operation.

Another object is the provision of such a can body flanging head wherein the pilot of the head is slightly smaller than the inside diameter of the can body to be flanged and is of sufficient length to support the inside surface of the tearing strip portion of the body so that straining of the body side walls adjacent the end of the body will be eliminated.

2

Another object of the invention is the provision of such a can body flanging head wherein the pilot and the sectional outside support ring provide wall confining guides for the body during the flanging operation so that the flange produced will be of a desired curvature having a line of bend beginning beyond and away from the outer score line of the tearing strip portion of the body so that fracture or rupture of this score line is prevented.

Numerous other objects and advantages of the invention will be apparent as it is better understood from the following description, which, taken in connection with the accompanying drawings, discloses a preferred embodiment thereof.

Referring to the drawings:

Figure 1 is a part sectional and part elevational view of a can body flanging mechanism having a flanging head embodying the instant invention and showing a can body in place with parts broken away;

Figs. 2 and 3 are enlarged sectional details of a portion of the flanging head illustrated in Fig. 1 and showing the parts in different positions, with an end portion of a can body before and after flanging, with parts broken away;

Fig. 4 is a sectional view taken substantially along the line 4—4 in Fig. 1 with parts broken away;

Fig. 5 is a perspective view of a tearing strip can body to be flanged; and

Fig. 6 is an enlarged sectional view of the tearing strip portion of the body shown in Fig. 5 after the completion of the flanging operation.

As a preferred embodiment of the invention the drawings illustrate principal parts of a flanging mechanism which includes a pair of flanging heads 11 for flanging sheet metal cylindrical cans A (Fig. 5) having an encircling tearing strip B set off by a pair of spaced and parallel score lines C disposed closely adjacent the flange edge D of the body. In the mechanism a can body to be flanged is placed endwise between the two heads in the usual manner and the heads move inwardly against the ends of the body to effect the flanging operation. It should be understood that usually a can body has only one tearing strip B and hence only one flanging head will be needed with the tearing strip end of the body.

However, to simplify the presentation of the present construction the two flanging heads 11 will be assumed to be identical in construction and operation, and a description and explana-

tion of one will suffice for both. Each flanging head includes a short cylindrical pilot 12 mounted on the inner end of an actuating rod 13 carried in a sleeve 14 slidably disposed in a bearing 15 of a frame 16 which may be the main frame of the flanging mechanism. The actuating rod 13 is reciprocated in any suitable manner in time with the other moving parts of the mechanism to shift the pilot 12 into and out of flanging position.

The pilot 12 is formed with an outer cylindrical can body supporting and confining surface 21 having a diameter slightly less than the inside diameter of the can bodies A to be flanged, so that the ends of the bodies will nicely fit over the pilot. This surface is of sufficient length to extend inside the can body for a distance beyond the innermost score line C so that the tearing strip portion B of the body is fully backed up or supported along its entire extent when a body is in position on the pilot. The inside confining surface 21 merges into an outwardly curved flanging seat 22 formed in a larger diameter base portion 23 of the pilot 12.

The inside confining surface 21 of the pilot 12 is surrounded by a sectional outside support flanging ring 25 which is formed with a plurality of contiguous hingedly mounted ring sections 26 (see Figs. 1 and 4). Each ring section 26 at its base is formed as a segmental toggle link 27 having curved or rounded end trunnions 28, 29. The curved inner trunnions 28 are freely disposed in a similarly curved hinge seat 31 of disposed in a similarly curved hinge seat 31 of pilot 12 which seat extends completely around the pilot and which is formed partly in the outer periphery of the base portion 23 of the pilot and partly in an annulus 32 secured by screws 33 to the base portion of the pilot.

The outer curved or rounded trunnions 29 of the ring sections 26 are also freely disposed in a curved hinge seat 35 which extends completely around the inner surface of an annular retainer ring 36 threadedly secured to the outer periphery of a disc 37 formed as an integral part of the inner end of the sleeve 14. The inner surface of the disc is provided with a flat seat 38 which bears against the outer trunnions 29 and keeps them in place in their curved hinge seat 35.

Thus by movement of the sleeve 14 along the pilot rod 13, the disc 37 may be shifted toward and away from the base portion 23 of the pilot. This shifting of the disc hinges or swings with a pivotal movement all of the ring sections 26 simultaneously on their rounded end trunnions 28, 29. For this purpose the sleeve 14 is reciprocated in its bearing 15 in any suitable manner and in time with the other moving parts of the mechanism.

The toggle link portion 27 of each of the ring sections 26 is formed with an intermediate laterally projecting neck 41 which extends inwardly toward the other or opposite flanging head, all of the neck sections thereby providing an annulus which is disposed outside and adjacent the pilot confining surface 21. This neck portion is formed with a curved body wall confining surface 42 for direct cooperation with the pilot confining surface 21. The confining surfaces 42 of the ring sections are of sufficient length to cover the tearing strip portion B of a can body A as it rests on the pilot 12 and when the ring sections are in operative position, as will now be explained. This surface terminates at its inner end in a curved flanging seat 43 for co-

operation with the flanging seat 22 of the pilot 12.

In operation a can body A to be flanged preferably is placed in any suitable manner between the two spaced apart flanging heads 11 so that the ends of the body are in alignment with the heads. The heads are then moved toward each other simultaneously to telescope the body over the pilots 12. During this inward movement of the heads the pilot rods 13 and the sleeves 14 move together as a unit. The disc 37 then is in a normal position, i. e., slightly spaced away from the pilot base 23, as shown in Fig. 3. This relation of disc and pilot holds the ring sections 26 in an outwardly hinged or open position, as shown in that figure. As the heads continue to move toward each other, the body A slides along the pilots without any diametrical straining or stretching.

As the flange edges D of the body approach the curved flanging seats 22 in the pilots 12 (this position being shown in Fig. 2) the ring sections 26 of the outside flanging ring 25 move inwardly into closed position around the outside of the body. The flanging ring is in closed position in Fig. 2. This has been brought about by a relative movement between the sleeve 14 and the pilot actuating rod 13. As the can body comes into the position of Fig. 2 the sleeve moves inwardly at an increased rate of travel over that of the pilots and thus hinging of the ring sections 26 inwardly on their trunnions 28, 29 takes place. This inward movement of the ring sections 26 brings their confining surfaces 42 into engagement with the outside of the can body with a slight pressure providing a slip grip while still permitting the body to move toward the flanging seat 22.

The closed ring sections 26 thus form a continuous engaging annular supporting ring around the outside surface of the can body adjacent its ends. At the tearing strip end of the body this supporting ring fully backs up and supports the tearing strip portion B and thereby prevents fracture of the score lines at this end of the body during the flanging operation which follows immediately.

In this closed or operative position of the ring sections 26 their outside curved flanging seats 43 are in spaced relation to the curved flange seats 22 of the pilots, as best shown in Fig. 2. This provides an accurate curved forming channel or pass between the curved seats of a dimension substantially that of the thickness of the can body wall. Hence as the inward travel of the heads 11 continues, the flange edge D of the can body is forced into this forming channel and is thus accurately curved outwardly into a flange E (Fig. 6) for the body.

During this flange forming operation the wall of the body is accurately confined between and guided by the seat 22 in the pilot 12 and by the seat 43 formed by the ring sections 26. Thus the curvature of the flange is controlled so that its line of bend begins well beyond and away from the outer score line C of the tearing strip B. In this manner the bending of the flange is prevented from taking place at what is the vulnerable part, i. e., at the score line and thus fracture or rupture of the body wall at this line is prevented.

The flanging action is terminated when the flange edge D of the body engages against the inner surface of the neck portion 41 of the ring sections 22 (Fig. 1). This neck portion thus

forms a stop which determines the length of the flange E.

Termination of the flanging action is immediately followed by stoppage of any further inward movement of the heads 11. The travel of the sleeves 14 and their discs 37 is immediately reversed while the pilot actuating rods 13 remain stationary momentarily. This reverse hinges the ring sections 26 outwardly into an open or non-operative position to release and clear the flanges E on the body, as best shown in Fig. 3. While the ring sections are in this open position, the pilot actuating rods move back with the sleeves and thus withdraw the pilots from inside the flanged body. This completes the cycle of operation of the flanging heads.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a device for flanging can bodies having a tearing strip set off by score lines disposed adjacent a flange edge of the bodies, the combination of a pilot over which a can body to be flanged is telescoped for a flanging operation, said pilot having a can body wall confining surface for backing up the inner surface of the tearing strip portion of the body and also having a flanging seat at the termination of said confining surface for bending the flange edge of the body outwardly into a body flange, a member movable independently of and relative to said pilot, a plurality of ring sections arranged around said pilot and hingedly connected to said pilot and to said member for forming a sectional outside support flanging ring engageable in a slip grip with the outer surface of a can body on said pilot and forming a continuous support completely around the body for backing up the tearing strip portion of the body during the flanging operation to prevent rupture of the score lines therein, and means for shifting said movable member relative to said pilot to hinge said ring sections into engagement with said body for the flanging operation.

2. In a device for flanging can bodies having a tearing strip set off by score lines disposed adjacent a flange edge of the bodies, the combination of a pilot over which a can body to be flanged is telescoped for a flanging operation, said pilot having a can body wall confining surface for backing up the inner surface of the tearing strip portion of the body and having a flanging seat at the termination of said confining surface for bending the flange edge of the body outwardly into a flange for the body, a member movable independently of and relative to said pilot, a plurality of ring sections arranged around and setting off a sectional outside support flanging ring surrounding said pilot, a pair of trunnions formed on each of said ring sections, said trunnions being disposed in annular seats formed in said pilot and in said movable member, and means for shifting said movable member relative to said pilot for rocking said ring sections into engagement with a can body on said pilot and for holding them in such engagement with a slip grip on the body for backing up the tearing strip portion of the body during the flanging operation to prevent rupture of the score lines therein.

3. Means for flanging can bodies, comprising a pilot for internally supporting a tubular can body having a weakened area therein set off by score lines, said pilot having a peripheral hinge seat spaced longitudinally outwardly from the end of the can body to be flanged and a peripheral flanging seat disposed between said hinge seat and said can body end, a flanging ring member composed of a plurality of ring sections each having a bearing portion freely mounted in said hinge seat for swinging movement towards and away from said internally supported can body, means engaging said ring member outwardly of said pilot, and means for effecting relative movement between said pilot and said ring member engaging means axially of the pilot to swing the ring member on its said hinge seat into exterior slip grip clamping engagement with the weakened area of the internally supported can body for backing up said area during the flanging operation on the body end by said flanging seat on the pilot to insure against rupture of said score lines.

4. Means for flanging can bodies, comprising a pilot for internally supporting a tubular can body having a weakened area therein set off by score lines, said pilot having a peripheral hinge seat spaced longitudinally outwardly from the end of the can body to be flanged and a peripheral flanging seat disposed between said hinge seat and said can body end, a flanging ring member composed of a plurality of ring sections each having a bearing portion freely mounted in said hinge seat for swinging movement towards and away from said internally supported can body, a retainer ring engaging said flanging ring member outwardly of said pilot, and means for moving said retainer ring relative to said pilot to swing the flanging ring member on its said hinge seat into exterior slip grip clamping engagement with the weakened area of the internally supported can body for backing up said area during the flanging operation on the body end by said flanging seat on the pilot to insure against rupture of said score lines.

5. Means for flanging can bodies, comprising a pilot for internally supporting a tubular can body having a weakened area therein set off by score lines, said pilot having a curved peripheral hinge seat spaced longitudinally outwardly from the end of the can body to be flanged and a curved peripheral flanging seat disposed between said hinge seat and said can body end, a flanging ring member composed of a plurality of ring sections each having an angularly and inwardly extending enlarged bearing portion of substantially circular cross section freely mounted in said hinge seat for swinging movement of the ring member towards and away from said internally supported can body, said ring sections each also having an oppositely disposed angularly and outwardly extending enlarged bearing portion of substantially circular cross section, an annular retaining ring spaced outwardly from and surrounding said pilot and having a curved bearing seat engaging said last mentioned bearing portions of said flanging ring member sections, and means for moving said retaining ring axially of said pilot for swinging the multi-section flanging ring member on its said hinge seat into exterior slip grip clamping engagement with the weakened area of the internally supported can body for backing up said area during the flanging operation on the body end by said flanging seat on the pilot to insure against rupture of said score lines.

6. Means for flanging can bodies, comprising a pilot for internally supporting a tubular can

7
body having a weakened area therein set off by score lines, said pilot having a curved peripheral hinge seat spaced longitudinally outwardly from the end of the can body to be flanged and a peripheral curved flanging seat disposed between said hinge seat and said can body end, a flanging ring member composed of a plurality of ring sections each having an enlarged curved bearing portion freely mounted in said hinge seat for swinging movement of the ring member towards and 10 away from said internally supported can body, said flanging ring sections also having curved flanging seats for cooperation with the correspondingly curved flanging seat on said pilot to form a channel therebetween when the ring is 15 disposed in operative position against a can body supported by said pilot to confine and accurately form the flange on the can body in predetermined spaced relation to said score lines, and means engaging said ring member and movable relative 20 to said pilot for swinging the ring member on said

hinge seat into exterior slip grip clamping engagement with the weakened area of the internally supported can body for backing up said area during the flanging operation on the body end by said flanging seat on the pilot to insure against rupture of said score lines.
